UNITED STATES PATENT OFFICE.

MORRIS SCHOENFELD, OF RORSCHACH, SWITZERLAND.

MACHINE FOR PUNCHING JACQUARD-CARDS.

987,259.

Specification of Letters Patent. Patented Mar. 21, 1911.

Application filed July 28, 1910. Serial No. 574,253.

To all whom it may concern:

Be it known that I, MORRIS SCHOENFELD, a citizen of the United States, and a resident of Rorschach, in the Canton of St. Gall, Switzerland, have invented certain new and useful Improvements in Machines for Punching Jacquard-Cards, of which the following is a specification.

My invention relates to improvements in machines for punching jacquard cards suitable for use in embroidering machine jacquards and the principal object is to increase the speed of operation and therefore the output of the punching machine without sacrificing safety and accuracy.

In the present instance my invention embodies certain broadly new features but in the application of my invention I have employed many of the elements which form the subject matter of U. S. Patent No. 627,256, as a basis for the machine and I will describe my invention as applied to such general construction, to simplify the present case, though it is to be understood that the present mechanism and the general form of the machine to which the same is applied may be varied without departing from the spirit and scope of my invention. In the construction shown in said U. S. patent, which is the best structure so far known to me there are certain elements for perforating a paper strip or jacquard card, which are arranged to produce various perforations in transverse alignment, each transverse line of perforations representing one stitch of the embroidering machine when the card is used in the jacquard of an embroidering machine. The tambour frame of the embroidering machine is moved in relation to the needles after each operation of the needles to form the stitch and in the jacquard most commonly used at present two or more movements of different units are combined to produce the proper final movement in the tambour frame. In the card punching machine shown in said U. S. patent there are several (four) stitch determining elements which actuate perforating elements and each stitch determining element serves to select from a group of punching elements whereby the location of the perforations in each transverse row of the card are determined and the location of which determines the stitching position of the tambour frame of the embroidering machine. In the punching machine referred to the stitch determining

elements consist of drums having pins extending from the periphery which pins are arranged spirally thereon, and the spirals run reversely on the opposite halves of the drums. These stitch determining elements are operated by the operator of the machine through mechanism described in said patent and by changing the positions of these various drums they place the various punching elements into operative condition for perforating the jacquard card and when the drums have been properly positioned for a stitch the punching mechanism is set into motion and the card is perforated. In such structure, however, the machine can not be set into operation to perform the punching operation unless the stitch determining elements are locked and the stitch determining elements are locked until the punching operation is completed. It is obvious, therefore that the machine must start, punch and come to a stop again before the stitch determining elements can be reset for a new stitch, thus making the speed of the machine limited.

It is the object of my present invention to overcome this objection whether employed in the construction above set forth or some other, by providing mechanism wherein the operator can proceed to lay out a new stitch before the machine has performed the punching operation or at least before the parts come to a complete stop, so that by the time the punching is completed the operator will have positioned the stitch determining elements and will be ready to set the machine into operation to perform the new punching operation. If the operator be skillful he can, by quick action in positioning the determining elements, cause the machine to operate practically continuously, that is, without letting the shaft and its cams come to a complete stop. In one form of my invention I make it possible to set the machine so that it will run continuously so that the operator will be required to position the determining elements before the punching mechanism comes to a stop, or rather, before it has completed one punching operation and commences the next one, thereby keeping up the speed of the operator. All this is accomplished without decreasing the efficiency or accuracy of the machine by employing certain automatic mechanism which will retain the elements of the punching mechanism in the position in which they are

placed by the stitch determining elements until the punching is completed and by automatically releasing the stitch determining elements when the retaining mechanism has entered into action, so that the stitch determining elements can be reset ready for the next operation. By the time the punching mechanism has completed its function the punching elements will be again brought into condition to be acted upon by the determining elements which latter were newly positioned as described. I employ proper locking mechanism to insure accuracy, but the mechanism is only locked for a brief period. The locking mechanism forms one of the principal parts of the present case, as well as the mechanism for releasing the determining elements and retaining the punching elements during the punching operation.

A full embodiment of my invention in the preferred form will be apparent in the detailed description hereinafter.

In the drawings forming a part of this application, Figure 1 is a longitudinal section through the punching machine with the parts in their starting position, Fig. 2 is a similar view with the parts in a different position, Fig. 3 is a horizontal section showing the starting and stopping mechanism, Fig. 4 is a detail view showing one of the lever actions, Fig. 5 is a longitudinal section showing the stitch determining mechanism and punching mechanism, Fig. 6 is a similar view with the parts in a different position, Fig. 7 is a similar view with the parts in a different position, Fig. 8 is a detail view showing certain lever actions, Fig. 9 is an elevation of part of the punching mechanism, Fig. 10 is an elevation of one of the punch selecting slides, Fig. 11 is a similar view of another slide, and Fig. 12 is a plan view of one of the parts.

I will first describe that branch of the mechanism which relates to the control of the stitch determining elements which is shown more clearly in Figs. 1 to 4. Herein I have shown the bed plate 1, on which rest the side plates 2, and the latter serve as supports for the various shafts and working parts on the lower part of the machine. The punching block and punches are only indicated in dotted lines in these views as they are fully shown in the other views of the drawings and they will be hereinafter fully described. It may be here stated that the machine shown in the U. S. patent referred to herein may be employed except in so far as parts of the same are superceded by the device herein and as such construction is fully described in that patent I will refer to only such parts of the complete machine as may be necessary to teach the application of my invention. In the construction referred to in the said patent there are cer-

tain drums e' e^2 , e^3 , e^4 , carrying the punch operating elements (pins) e , which are arranged spirally on the drums in a certain way and these drums are revolved by the operator in connection with certain mechanism by which the operator is able to follow the movements on the pattern; and these drums, which I shall herein call the stitch determining elements, as well as the mechanism for operating them is fully set forth in said patent and the same may be and preferably are, employed in the present construction. In the present construction these determining elements are carried upon the shafts as shown in said patent and are similarly operated. The mechanism for controlling the operation of these elements, or rather locking them relative to certain other mechanism is here new.

The shaft 60 which is part of the stitch determining mechanism is provided with a gear wheel 58 which moves with the shaft, and therefore with the stitch determining mechanism. There is a stud 63 arranged near the gear wheel on which is fulcrumed a lever 61, the upper end of which carries a dog 59, which is so positioned that it can be thrown into or out of engagement with the teeth of the gear 58 and thereby prevent or permit the operation of the shaft 60. It is through this dog that the stitch determining elements are prevented from being operated until certain conditions in the machine are present. The lower end of this lever 61 carries an engaging pin 62, while the upper end has an extension 73, which is provided with a pin 74. A shaft 21 supports an angular lever 75, 96, the forward end of which has a slot 75* in which the pin 74 engages, and by means of which engagement certain movements are imparted from the lever 61 to the lever 75, 96. The main shaft 18 of the machine carries certain operating cams, one of which is numbered 76, which is shown more fully in Fig. 1, etc.; and this cam carries a gear crown 77 on its periphery the purpose of which will appear. The shaft 18 is adapted to be driven from a source of power and by means of suitable controlling mechanism the shaft 18 may be started or stopped by connecting or disconnecting the shaft 18 with the source of power. In the present showing the pulley 101 on shaft 102 furnishes the power and by means of a lever the shaft 79 is thrown into or out of engagement with the pulley 101. I have shown the shaft 102 provided with one element 101 of a cone clutch and the shaft 79 which is adapted to be reciprocated longitudinally, is provided with the other element 99 of the cone clutch; and the whole clutch is incased in a shell 104 which has a flange 104* which serves as a brake for the clutch element 99 and therefore for the shaft 79. I have shown the shaft 79 journaled in the blocks 80 and 130

81 and its purpose is to transmit the operating force to the gear 77 and thus to the shaft 18. The shaft 79 carries a gear 78 which meshes with and operates the gear 77 and a spring 98 interposed between the block 81 and gear 78 tends to force the shaft 79 longitudinally in such a way as to cause the clutch elements 101, 99, to engage and thus revolve the shaft 79. So long as the 10 spring 98 is free to exert its effect on the shaft 79 the power from shaft 102 is imparted through the shaft 79, gears 78 and 77 to shaft 18.

On the perpendicular shaft 82 I have 15 mounted a throwing out lever 83, the hub of which is provided with arms 84 and 85 which straddle the shaft 79 and impinge the collar 100 carried thereon. The purpose of this lever is to force the shaft 79 in opposition to the spring 98 and by longitudinal displacement disengage the clutch elements to stop the operation of shaft 18. The arm 86 of the lever 83 carries a contact nose 87 which is engaged by a controlling lever.

25 On the stud 88 I have journaled a lever 89, which is provided on its upper end with a pin 90, which carries a roller 99 that travels in a groove 92 of the groove cam 76, and by means of this cam the lever 89 is periodically rocked. There is another lever 94 which is fulcrumed at 93 to the lever 89, and one end 94^b has a rocking contact with the lever 96, the spring 97, tending to retain the lever ends in contact with each 30 other. The other end 94^a of lever 94 has a pin 95 which is adapted to engage with the part 87 of lever 83.

Near the stitch determining mechanism I have provided a bracket 105 which supports 40 a stud 106 and on this latter is fulcrumed a two armed trigger 107 which serves to release the lever 61, controlling the locking mechanism. This trigger has an engaging shoulder 108, with which the pin 62 on lever 61 engages. A spring 109 connected to one end of the trigger and to the bracket 105 retains the trigger in contact with the lever 61. The other arm of the trigger 107 is connected with means operated from the shaft 45 18 for causing the lever 61 to assume different positions independent of any action of some of the other elements. A stud 127 is suitably supported in a bracket and serves as a fulcrum point for a lever 123. The latter has a roller 129 on the pin 128 which roller travels in the groove 130, of a cam 131 on the shaft 18 and on every revolution of the cam 131 the lever 123 is twice affected by the cam. There is fulcrumed to the lever 50 60 123 an arm 122 which operates the shaft 63 on which the lever 61 is carried. The rod 122 is passed through the end of an arm 121 which is secured on shaft 63, the same being the shaft which carries the lever 61 and the 55 65 pin 126 retains these parts in this relation.

Between the lever 121 and the collar 124 is a spiral spring 125 which forces these two elements apart.

On a stationary stud 112 I have mounted a three arm lever 111. One end of this lever 70 is connected with a rope 114 which serves to actuate the mechanism and corresponds with the starting rope in said patent and may be similarly connected and operated. The arm 110 of this lever is so positioned that it will 75 engage and trip the trigger 107 for releasing the latter. The other arm of this lever 111, is connected by a rod 113, with a bar 120 and this in turn is raised or lowered by the action of an eccentric 119. The latter is 80 mounted on the machine where the same may be easily operated by the operator turning the handle 118, and thereby the shaft 117 on which the eccentric is carried. The purpose of this will appear in the description of the 85 operation of the device.

Before passing to the remainder of the construction I will describe the operation of this part of the mechanism.

Let it be assumed that the stitch to be 90 recorded has been determined upon and the pin drums such as e' , e^2 , e^3 and e^4 , in said patent have been positioned, ready to operate through certain selecting elements for punching the card. The stitch determining 95 elements being set and the present mechanism being in the position shown in Fig. 1, the operator pulls the rope 114 in the direction of the arrow to set the punching mechanism into operation, after which he 100 lets the rope loose to allow the parts to assume their first position. I will first describe the device as operating with the handle 118 set as shown in Fig. 1, wherein it is necessary for the operator to initiate each 105 punching operation by pulling the rope 114. When the rope 114 is pulled it rocks the lever 111 on its fulcrum, resulting in the trigger 107 being rocked against the action of its spring 109, by the arm 110 of lever 111 and 110 the result will be that the cam portion 108 of the trigger will be released from engagement with the pin 62 of lever 61. The rod 122 is so positioned by the action of cam groove 130 on the roller of lever 123, that the rod 122 will be in its right hand position 115 (Fig. 1) where the spring 125 will tend to force the arm 121 to the right. While the pin 62 was in engagement with the trigger the dog 59 was retained out of engagement 120 with the gear 58, which permitted the setting of the stitch determining elements as stated. When the trigger is pressed by the arm 110 it leaves the arm 121 subject to the action of the spring 125 and as a result 125 the arm 121 will be rocked, moving the shaft 63 and with it the lever 61, until the dog 59 is thrown into the teeth of the pinion 58. The stitch determining elements are now locked and can not be repositioned for the 130

next stitch until the dog 59 is released from the pinion in the manner which will appear.

When the lever 61 is rocked, it will, through its engagement with lever 75, 96 cause the latter to rock and by means of the end 94^a the arm 94 will be rocked so that its engaging pin 95 will be brought out of the path of the pin 87 of the shifting lever 83. In Fig. 3 the parts are shown in the condition they are in in Fig. 1, which is their first position when the spring 98 is held under tension by the lever 83 and the shaft 18 is idle. When the lever 83 is released by the rocking of lever 94 as above stated it will be free to rotate sufficient to permit shaft 79 to be displaced. Upon the freeing of the lever 83 the spring 98 pressing against the gear 78 forces the shaft 79 in the direction of the arrow, the gears 78 and 77 being in engagement with each other at all times. The movement of the shaft 79 longitudinally brings the clutch elements 99 and 101 into frictional engagement. Since the shaft 102 and its clutch element are continually operating, the shaft 79 will now be revolved and by reason of the gears 77 and 78 the movement will be imparted to the shaft 18 which operates the punching mechanism.

When the shaft 18 rotates, the several cams carried thereby rotate also, causing the punching operation and also causing a change in the locking mechanism. When the shaft 18 begins to turn the position of the punch locking slides will be retained by the mechanism hereinafter described, in the position necessary to perform the punching operation, but the stitch determining elements will be so affected, before the shaft 18 has proceeded far that they need not remain as set but can be returned to be reset for a new stitch without waiting for the completion of the punching operation.

Soon after starting, the cam groove 130 will rock the lever 123 and thereby the rod 122 will be moved to the left. The engagement of the pin 126 with the arm 121 will then rock the shaft 63 and lever 61 to disengage the dog 59 from the pinion 58. As the dog is thus released the operator can now proceed to lay out the next stitch by repositioning the stitch determining elements by the mechanism described in the said patent. When the lever 61 is thus rocked in a direction reverse to its first movement it also rocks the lever 75, 96, and this in turn rocks the arm or lever 94 on its fulcrum 93. The result will be that the pin 95 on the lever 94 will be brought again in the path of the pin 87 on the throwing out lever 83. When the shaft 18 is nearing the completion of its revolution the cam 76 through the groove 92 will rock the lever 89 to the left and since the lever 94 is carried thereby and since the position of lever 94 is now such that the pin 95 is in the path of pin 87 the

pins will be engaged as the lever 89 rocks and lever 83 will be rocked back to its first position. As it does so the arms 84, 85, will reciprocate shaft 79, compressing the spring 98 and releasing the clutch until the shaft 79 is no longer driven. The return action will engage the clutch element 99 with the flange 104^a and cause the shaft 79 to stop by a braking action. The mechanism is thus automatically stopped after each revolution of the shaft 18 and after the completion of one punching operation and will remain so until the operator again initiates an action. When the operator releases the rope 114 the action of the spring 109 on the trigger will move its engaging part 108 again into the path of the pin 62, ready for the second operation.

The machine automatically stops after each punching operation unless the operator has been able to lay out the second stitch by the time the first punching operation is completed in which case he pulls rope 114 before the machine stops and it goes on to perform the second punching operation. If the machine is to be run continuously so that the operator will have to set out his new stitch while the punching is being completed the setting handle 118 is turned to the position shown in Fig. 2. The effect of this will be to raise the bar 120 on the eccentric 119, thus raising the rod 113 and rocking the lever 111 until the arm 110 presses the trigger out of the path of the pin 62. There will thus be nothing to engage the lever 61 at each operation and therefore it will be subject to the effect of each movement of the rod 122 and as a result a new movement is initiated by the time the last one is being completed and as a result there will be no stopping of the shaft 18 and the punching mechanism though the stitch determining mechanism will be automatically locked for a brief period of each operation. The operator will now be obliged to lay out the second stitch before the machine has completed the first and so on. In this way the machine will not have to stop after each punch and then be started again and the operator will be obliged to keep up in his speed.

If the dog 59 should accidentally engage the top of one of the teeth of the pinion 58 no trouble will result, because the action of the rod 122 to the right is imparted through the spring 125 which may be resisted. Should the dog 59 engage on top of a tooth the rod 122 and all the other mechanism will proceed as before.

The next branch of my invention relates to the punching mechanism and to its co-operation with the safety mechanism just described. The details of this part of my invention are more clearly shown in Figs. 5 to 12. There is provided a punching mechanism which I have shown constructed gener-

ally on the plan of that shown in the said U. S. patent previously mentioned and the present mechanism may be carried out in the general construction shown in such patent.

5 There is provided a punching block 4, disposed in the machine where it will have proper location with relation to the punching elements. Above the punching block 1 have provided a punching plate 5 and a 10 pressing plate 6, between which the paper strip or pattern roll 64 travels and these plates are provided with a double row of perforations 6^a, 6^b, which are in stepped relation, as shown in Fig. 12. The pattern roll 15 is fed from a suitable supply roll, under the roller 65, over the roller 66, between the plates 5 and 6 and onto a roller 69 on the shaft 70, and the feed rollers 67 and 68, interposed between the plates 5, 6, and roll 20 69 serve to propel the paper intermittently at regular intervals. For operating the feed rollers 67 and 68 I prefer to use the same mechanism as that shown in said U. S. patent.

25 In line with and adapted to enter the apertures 6^a, 6^b, of the punching plates I have arranged the rows of punching elements 9 and 9^a the former alining with the apertures 6^a and the latter with the apertures 6^b and each punching element is provided with an enlargement 9^c. The punching rods pass through an angular guide bar 7, with their enlargements 9^c below, so that the bar 7 limits the upward movement of the 30 punch bars. For raising the punch bars and operating them in connection with the slide selectors I prefer to employ mechanism similar to said patent. For this purpose there is an angle metal bar 8, the two flanges 35 8^a of which have apertures for the reception of the rods 9 and 9^a and the apertures aline with the apertures 6^a and 6^b. The enlargements 9^c lie between the bar 7 and the lower flange 8^a of the bar 8. The bar 8 is provided with an open pocket above the upper flange 8^a for the engagement of the locking slides, and the bar is supported above by 40 links 11, which are hung on the end of a lever 12. This lever fulcrums on a support 45 13 and one arm 14 thereof is provided with a pin 15 carrying a bowl 16 which engages in the groove 16^a of a cam 17 carried upon the main shaft 18, and by means of this cam the lever 12, 14 is rocked twice at each 50 revolution of the shaft 18 and the bar 8 is therefore raised and lowered twice.

For selecting the various punching rods and locking certain ones whereby they will be made to move with the bar 8 in its downward movement I have provided selecting or locking slides which coöperate with the bar 8. They are arranged in two sets and are numbered 10 and 10^a respectively and are shown in detail in Figs. 10 and 11. The 55 slides 10 and 10^a are arranged longitudinally

side by side with their ends projecting into the pocket 8^b of the bar 8, where they are guided by the upper and lower grooves 8^c. Each slide has a rounded part 10^e, on which the slide is adapted to rock and the upper 70 projections 10^f engaging with the bar 8 prevent any disarrangement of the slides. These slides are so operated that during their inactive period they lie away from the punch rods, while when they are advanced 75 they cause their respective punch rods to be moved upon the downward movement of the bar 8. For each rod 9 there is a slide 10, and for each rod 9^a there is a slide 10^a arranged to engage the rods above. I have 80 provided automatic means for advancing the several slides when brought into operative relation therewith and there is mechanism whereby the stitch determining device first positions these slides for movement by said 85 automatic means, and there is other means whereby the slides are preserved in the position thus placed until the punching is complete so that the stitch determining mechanism may be again operated without having 90 to retain the slides in their position by the determining mechanism during the punching operation.

There are provided two cross shafts 45 and 47 which carry the push plates 46 and 95 53 by means of which the locking slides are reciprocated; the plate 46 serving to engage in the slots 10^b and move the slides 10^a, while the plate 53 engages in the slots 10^b and reciprocates the slides 10. The space 10^d prevents the plate 46 from affecting the slides 10, so that the two sets of slides will be affected only by their respective push plates. The shafts 45 and 47 lie above the slides and are adapted to engage only such slides of 100 their respective sets as are raised into engaging position. The shafts 45 and 47 are periodically rocked from the main shaft 18, one slightly prior to the other, so that the two sets of slides will be reciprocated successively for the purpose of bringing the perforations caused by the two sets of punches in a transverse line.

The device for rocking the shaft 47 consists of an arm 48 secured to the shaft, which 115 is fulcrumed to a connecting link 49 and the latter to a lever 50, which fulcrums on a support 51. The other arm of the lever 51 carries a bowl 52 which travels in the groove 43 of a disk cam 44 carried on the shaft 18. 120 Each revolution of cam 44 causes the lever 51 to be rocked, and the movement is transmitted through the link 49, and lever 48 to the shaft 47, which it oscillates. The shaft 47, oscillating, imparts through the push 125 plate 53 a reciprocating movement to such of the slides 10 as are raised, moving them first to the left so that the rounded portions 10^e will come over their respective punch rods and then back to their first position. 130

The shaft 45 is rocked in a similar manner to the shaft 47 but the movement is in advance of that of shaft 47. There is an arm 39 on shaft 45, corresponding to the arm 48, and it is fulcrumed to a link 38, which connects with a lever 40, rocking on a support 41. The other arm of this lever has a bowl 42 engaging in the groove 43 of the cam 44, in advance of the bowl 52 of the lever 50. The movement of the shaft 45 is thus timed to precede the movement of shaft 47 so that the slides of the two sets will be reciprocated successively.

The mechanism for moving the slides into operative relation with their push plates 46, 53, forms a novel and important part of the present invention. On the stud 21 I have provided a rocking lever 22, which carries a roller 24 on the pin 23 and this 20 roller is retained in contact with a cam arm 26 on the shaft 18 by means of a spring 25. It will be thus apparent that the lever 22 is rocked at each revolution of the shaft 18.

The arm 22^a on the shaft 21 is provided 25 with a plate 20 which is provided with as many apertures as there are slides 10 and 10^a and through these apertures rest the pins 19. These pins are preferably rivet shaped, with their heads 19^a normally resting on the plate 20 and their shanks 19 passing through the apertures and below the plate 20, where they are actuated by the stitch determining mechanism. The pins 19 are carried upwardly by the plate 20 and 30 their function will be more clearly understood in the description of the operation of the mechanism. On the plate 20 there are ears 27, spaced apart, which act as supports for the arms 29 which are fulcrumed there- 35 to; and these arms 29 carry a supporting plate 30 which rocks on its supporting arms and which is adapted to engage under the heads of the pins 19 and retain them in an elevated position to preserve their position 40 to; and these arms 29 carry a supporting plate 30 which rocks on its supporting arms and which is adapted to engage under the heads of the pins 19 and retain them in an elevated position to preserve their position 45 when the stitch determining mechanism is released. A spring 32 which surrounds the shaft 28, on which the arms 29 rock have one end engaging in the shaft and the other against the arms 29, whereby the plate 30 50 will be retained in the position shown in Fig. 5 unless resisted. The plate 30 is provided with an upwardly extending arm 31 which is adapted to be engaged by an arm 33 for the purpose of tripping the plate 30 to release it from engagement with the pins 19. The arm 33 is carried on an arm 34 which rocks with the shaft 35 and this latter is operated by means of a bifurcated arm 36 which straddles a pin 37 on the link 38, the 55 operation of which has been described.

As previously stated there is a pin 19 for each of the slides 10, 10^a, which the pins are adapted to raise into engagement with their respective push plates. These pins 19 are 60 operated by the stitch determining mecha-

nism to select certain of the punching elements for operation. The drums 55, which have been previously referred to in the description of the safety mechanism are the same as the drums *e'*, *e²*, *e³*, *e⁴*, of the said U. S. patent and each has a double set of pins 56 arranged in reverse spirals across their periphery, with a space *L* between the sets sufficient to permit the pins 19 to rest unaffected when the drums are in their normal position. The position of the parts in Fig. 5 may be considered the normal or starting position, where the pins 19 rest with their heads 19^a on the plate 20 and the plate 20 in its low position. The drums 55 are operated 70 by means of the mechanism shown in said patent and the locking and controlling mechanism for the shaft 60 has been previously described.

With the parts in the position shown in Fig. 5 they are ready for a punching operation. As the shaft 18 commences to revolve the roller 24 will rise on cam 26 and the lever 22 will be rocked. This will move the plate 20 upwardly, raising the pins 19 above the pins 56. The drums 55 are now in such a position as will determine the next stitch, when some of the pins will come under certain of the raising pins 19. The roller 24 now rides down on the cam 26 and the rocking of lever 22 will move the plate 20 downwardly. Those pins 19 which are over any of the pins 56 of the stitch determining mechanism will remain in their elevated position, while those not engaged by the pins 56 will ride down with the plate 20. When the pins 19 arose with the plate 20 all the slides 10, 10^a were raised at their rear ends and when the plate 20 descended those slides which are engaged by the pins 19, affected by the pins 56, remain raised and the others descend with their pins 19. When the plate 20 descended, as just described, the pins 19 which were resisted by the pins 56 and held elevated, will resist the downward movement of the plate 30 on one edge and as a result the plate 30 will be tilted, rocking on the arms 29, in resistance to the springs 32; and when the edge of the plate 30 passes the heads 19^a of the pins 19 the plate 30 will 110 be rocked back again into its former position. When the plate 30 tripped over the heads of the raised pins 19, it entered between the heads of the lower pins and the heads of the upper pins as shown in Fig. 6, 115 thus preserving the pins in the position first caused by the pins 56. In other words it assumes the support of the pins 19 which were engaged by the pins 56 so that if the latter are moved away for the laying out of another stitch the condition of the selecting slides is preserved until they have performed their function. The stitch determining mechanism need no longer be retained in the position set for this punch because the sup- 120 125 130

port of the raised pins 19 is now taken up by the plate 30. In fact, when the plate 30 has returned as previously described, the mechanism for operating the return of the drums 55 to their normal or starting position has come into action and returned them, such mechanism being the same as in the said U. S. patent referred to herein. From this time the stitch determining mechanism is unlocked by the mechanism described in the first part of this case and instead of waiting for the punching operation to be completed, the operator can proceed to lay out the next stitch by positioning the drums 55 ready therefor. He can not, however, initiate this next stitch until the operation now being considered has been completed, because of the protective system described.

Some of the pins 19 are now resting on the plate 20, while others are held raised by the plate 30. Those held up are supporting their respective slides 10 or 10^a in an elevated position, when the push plate 53 will lie in the slots 10^b of such slides 10 as are raised; while the push plate 46 will lie in the slots 10^b of such slides 10^a as are raised. The reciprocation of the slides is now possible. The lever 50 is first rocked by the action of cam 44 on its bowl, and as a result the movement will be transmitted by the link 49 and lever 48 to the shaft 47 and push plate 53. This will move the selected slides 10 forward, when their rounded portion 10^c is over the tops of their respective punching rods 9. The first rise of the cam groove 16^a of cam 17 will now operate on the bowl 16 to raise the lever 14, depress the opposite end 12 and likewise the link 11 and bar 8. The punching bars 9 which are locked by their slides 10 will be forced through the paper 64, while those not affected by their slides will rest upon the surface of the paper and will not pass through it. Upon the return movement of the bar 8 the rods which perforated the paper as well as the others will be raised again; and the paper feed mechanism will operate to move the paper along sufficient to bring the perforations just made, in the transverse line of the advance punch rods 9^a. The mechanism for this is preferably the same as in said U. S. patent and the purpose is the same: That is, the transverse rows of perforations can be placed closer together, with some of the perforations overlapping others, which could not be done were all the punch rods in one row. The slides 10, which were advanced for the operation described are now returned by the return operation of the push plate 53. As soon as this takes place the cam groove 43 acting on the roller 42, rocks the lever 40, moving the link 38 and thus the lever 39 and shaft 45. This action moves the push plate 46 and advances such of the slides 10^a as are raised, forward, and

over their respective punch rods 9^a similar to the action of the previous push plate. The bowl 16 will now be acted upon by the second rise of the cam groove 16^a and the bar 8 will be depressed again. This time 70 such punch rods 9^a as are locked by their slides 10^a will be forced through the paper and by reason of the repositioning of the latter the new perforations will come in line with the first mentioned perforations. 75 The bar 8 will now return the punch rods. As the lever 40 was rocked to move the slides 10^a forward the pin 37 on link 38, rocked the lever 34, carrying the rod 33 up and away from the arm 31 of the plate 30. 80 Upon the return movement of the lever 40 and its associated parts the rod 33 will trip the arm 31 and release the plate 30 from the heads of the raised pins 19, when the latter will return to their lower position and the 85 machine will be ready for the next successive stitch. If the stitch determining elements have been repositioned by this time and the starting mechanism initiated the previously described operations will be 90 repeated without any cessation. Otherwise the shaft 18 will come to a stop and will remain there until the next operation is initiated by the mechanism described herein.

From the above it will be apparent that 95 the mechanism is safe and effective, but greater speed and increased work are possible. The locking of the stitch determining mechanism takes place as soon as the machine operation is initiated, but instead of 100 remaining locked until the entire punching is completed the stitch determining mechanism is unlocked automatically as soon as the support of the pins 19 which have been raised by the stitch determining mechanism, 105 has been taken up by the plate 30. In this way the stitch determining mechanism is free soon after the punching operation is initiated so that the next stitch can be laid out while the punching is being completed. 110

While I have carefully described in detail one form of mechanism embodying my invention I am not limited thereto, as the broad objects of my invention permit of changes in the mechanism by which it is 115 carried out.

Having described my invention what I claim is;

1. In a jacquard card punching machine, 120 punching elements for perforating the jacquard card, operating mechanism for the punching elements, stitch determining mechanism, means for throwing the punch operating mechanism into operation and means for locking the stitch determining mechanism, coöperating with said throwing in means, whereby the latter will not be operated except upon the operation of the locking mechanism and manually operated means for initiating the said stitch deter- 125 130

mining locking mechanism and the punch operating mechanism.

2. In a jacquard card punching machine, 5 punching elements for perforating the jac-
quard card, operating mechanism for the
punching elements, stitch determining mech-
anism, means for throwing the punch oper-
ating mechanism into operation and means
10 for locking said stitch determining mech-
anism, said throwing in mechanism being
operated by the said stitch determining
locking mechanism.

3. In a jacquard card punching machine, 15 punching elements for perforating the jac-
quard card, operating mechanism for the
punching elements, stitch determining mech-
anism, means for throwing the punch oper-
ating mechanism into operation and means
20 for locking said stitch determining mech-
anism, said throwing in mechanism being
operated by the said stitch determining
locking mechanism and manually operated
means for initiating said stitch determining
locking mechanism.

25 4. In a jacquard card punching machine, punching elements for perforating the jac-
quard card, operating mechanism for the
punching elements, stitch determining mech-
anism, means for locking the stitch deter-
30 mining mechanism and automatically oper-
ated means for releasing said locking means
before the completion of the punching oper-
ation.

35 5. In a jacquard card punching machine, punching elements for perforating the jac-
quard card, operating mechanism for the
punching elements, throwing in mechanism
40 for causing the operation of the punch
operating mechanism, stitch determining
mechanism and a locking mechanism there-
for, means for initiating the said throwing
in means and automatically operated means
45 for throwing out said punch operating
mechanism upon the completion of the
punching operation.

50 6. In a jacquard card punching machine, punching elements for perforating the jac-
quard card, operating mechanism for oper-
ating the punching elements, throwing in
55 mechanism for throwing said punch oper-
ating mechanism into operation, stitch deter-
mining mechanism, locking means for
locking the stitch determining mechanism,
manually operated means adapted to cause
55 the operation of said stitch determining
locking means and the said throwing in
means, automatically operated means for un-
locking said locking means before the com-
pletion of the punching operation and auto-
60 matically operated means for throwing out
said punch operating mechanism upon the
completion of the punching operation.

65 7. In a jacquard card punching machine, punching elements for perforating a jac-
quard card, operating mechanism for oper-
ating mechanism for the first part of
70 the operation of the punch operating mech-
anism and to unlock the same before the com-
pletion of the punching operation.

ating the punching elements, stitch deter-
mining mechanism and automatically oper-
ated mechanism adapted to lock the stitch
determining mechanism for the first part of
the operation of the punch operating mech-
anism and to unlock the same before the com-
pletion of the punching operation.

8. In a jacquard card punching machine, 75 punching elements for perforating a jac-
quard card, operating mechanism for oper-
ating the punching elements, stitch deter-
mining mechanism and locking mechanism
therefor, automatically operated means for
operating the said locking means, adapted
80 to effect the locking of the stitch determin-
ing mechanism and to effect the unlocking
thereof, before the punching operation is
completed, starting and stopping mech-
anism for the punch operating mechanism,
manually operated means for initiating the
85 starting of the punching mechanism and
means for throwing out said manually oper-
ated means whereby the punching mecha-
nism will operate continuously.

9. In a jacquard card punching machine, 90 punching elements adapted to punch the jac-
quard card, an operating shaft, operating
means for the punching elements operated
from said shaft, starting and stopping mech-
anism for the punch operating mechanism,
95 operated from said shaft, stitch determining
mechanism, having a gear, a lever having a
dog for engaging said gear to lock the stitch
determining mechanism, means automatic-
ally operated from said shaft and adapted
100 to positively operate said locking lever in
one direction to unlock the stitch determin-
ing mechanism and to resistably move said
locking lever in another direction to lock the
said stitch determining mechanism, manu-
ally controlled mechanism adapted to en-
gage said locking lever and means whereby
105 the said starting mechanism will be initiated
from said locking mechanism.

10. In a jacquard card punching machine, 110 punching elements for perforating the jac-
quard card, mechanism for selecting and lock-
ing the punching elements, whereby certain
of the punching elements will be operative,
stitch determining mechanism for affecting
115 the selection and locking mechanism, means
for completing the function of the stitch de-
termining mechanism after the latter has
initiated the selecting operation, whereby
the stitch determining mechanism may be
120 repositioned and means for operating said
punching elements.

11. In a jacquard punching machine, 125 punching elements for perforating the jac-
quard card, mechanism for selecting and lock-
ing the punching elements, whereby cer-
tain of the punching elements will be operative,
stitch determining mechanism for af-
fecting the selecting and locking mechanism,
means for completing the function of the
130

stitch determining mechanism after the latter has initiated the selecting operation, whereby the stitch determining mechanism may be repositioned, means for operating 5 said punching elements and means for returning the selecting mechanism after the completion of the punching operation.

12. In a jacquard card punching machine, 10 punching elements for perforating jacquard cards, slides for making the punching elements operative, pins for engaging said slides whereby the latter will be operated to affect the punching elements, stitch determining mechanism adapted to select from 15 said pins whereby certain of said slides may be operated, and automatically operated means for affecting the selected pins whereby their selective action will be carried out during the punching operation, whereby the 20 stitch determining mechanism can be repositioned and means for operating said punching elements.

13. In a jacquard card punching machine, 25 punching elements for punching jacquard cards, selective mechanism for the punching elements embodying selecting pins, stitch determining mechanism for raising selected pins, an automatically operated plate for engaging the selected pins and retaining 30 them in their operative position during the punching operation, whereby the stitch determining mechanism may be repositioned for the next operation and automatically operated means for releasing said plate from 35 the selected pins upon the completion of the punching operation.

14. In a jacquard card punching machine, 40 punching elements for perforating a jacquard card, locking elements for locking the punching elements by which the latter are made operative, pins for engaging the locking elements, means for raising said pins, stitch determining mechanism adapted to oppose the return of said pins whereby certain of said pins are selected, a plate moving 45 with the pin raising means and adapted to engage the selected pins and retain them in

their raised position during the punching operation, whereby they no longer depend upon the stitch determining mechanism, 50 which latter is free to be repositioned and automatically operated means for releasing said supporting plate when the punching operation is completed.

15. In a jacquard card punching machine, 55 punching elements for perforating a jacquard card and means for operating the same, reciprocating slides for locking the punching elements and thereby making them operative, means for reciprocating said 60 slides, pins for raising said slides into operative relation with their reciprocating mechanism, an automatically operating plate adapted to raise said pins, stitch determining mechanism adapted to resist the return 65 of the said pins whereby certain of the pins may be selected, a spring pressed element adapted to trip over the heads of the resisted pins upon the return of the said raising plate and to support the selected pins 70 during the punching operation and automatic means for releasing said plate from the raised pins after the punching operation.

16. In a jacquard card punching machine, 75 punching elements for perforating a jacquard card, operating mechanism therefor, mechanism for making the punching elements operative, stitch determining mechanism for affecting the selection of certain punching elements, means for continuing the 80 function of the stitch determining mechanism whereby the latter may be returned for repositioning and locking mechanism whereby the stitch determining mechanism is locked until its function is taken up by the 85 mechanism for continuing its function and unlocked thereafter.

Signed at St. Gall, in the Canton of St. Gall, Switzerland, this 18th day of July, 1910.

MORRIS SCHOENFELD.
